UNITED STATES PATENT OFFICE.

FRED L. HINKS, OF FORT DODGE, IOWA.

ROTATABLE SIGN.

Application filed June 2, 1928. Serial No. 282,363.

This invention relates to a sign apparatus and pertains particularly to a rotatable sign.

The primary object of the present invention is to provide a sign structure designed 5 to be rotated by the wind, of novel construction whereby a rotation at a moderate speed will be obtained.

Another object of the invention is to provide, in a sign, novel means for catching wind 10 to cause rotation of the same.

A still further object of the invention is to provide, in a rotatable sign, an improved means for mounting the same to permit free movement thereof.

15 The invention will be best understood from a consideration of the following detailed description taken in connection with the accompanying drawings forming part of this specification, with the understanding, however, 20 that the invention is not confined to any strict conformity with the showing of the drawings but may be changed or modified so long as such changes or modifications mark no material departure from the salient features 25 of the invention as expressed in the appended claims.

In the drawing:—

Figure 1 is a view in side elevation of the sign structure;

30 Figure 2 is a transverse section upon the line 2—2 of Figure 1;

Figure 3 is an enlarged detail sectional view of the central portion of the sign showing the supporting bearings;

35 Figure 4 is a detail sectional view of the central upper portion of a modified bearing structure.

Referring to the drawing in detail wherein like numerals of reference indicate corresponding parts throughout, the numeral 1 indicates generally the sign body embodying the present invention, a support therefor being indicated by the numeral 2.

The sign comprises a horizontally positioned elongated relatively wide rectangular frame 3 comprising the top and bottom bars 4 and 5 respectively and the connecting end bars 6. The bars of which the frame 3 is made up are relatively wide and the frame has 50 positioned therein the sign board 7 which is arranged to extend at an angle with respect to the side faces of the frame, that is, the board at one end has one face substantially flush with one side edge of one end rail while 55 at the other end the other face is substantially flush with the other end rail at the

opposite side edge thereof, thus forming the relatively long air pockets 8 one at each end of the sign.

The sign 7 is made up of a frame 7^a which fits within the frame 6 as shown in Figure 2, and has a covering sheet 7^b overlying each face.

These covering sheets may be made of metal or thin wood.

As is clearly shown in Figure 2, each of these pockets is of gradually decreasing depth from one end of the sign to the opposite end thereof.

The top and bottom rails 4 and 5 of the sign frame are provided intermediate their ends with the bearing bodies 9 and 10 respectively, each of which houses roller bearing elements 11. A supporting shaft 12 extends through the bearings 9 and 10 and is designed 70 to be vertically positioned to support the sign for rotation about a vertical axis. For the support of the vertical shaft 12, there is preferably provided a tubular post or standard 75 13 into which the lower end of the shaft 12 extends, the said lower end being provided with a relatively thick washer 14 which snugly fits within the post to maintain the shaft in position upon the longitudinal center 80 thereof, coacting with the centrally apertured 85 cap member 15 detachably mounted upon the upper end of the post, for this purpose, the shaft extending through the aperture of this cap as shown. The post 12 extends through the top and bottom rails of the board 7 between the sheets or plates 7^b.

Mounted upon the cap 15 is a bearing block 16 from which the post 12 extends, the upper surface of this block being provided with an annular ball race 17 for the reception of the 95 anti-friction balls 18, the lower surface of the bearing member 10 being provided with a similarly formed race-way 19 for the reception of the balls, thus forming an anti-friction support for the sign.

The ball bearing support and roller elements may be kept supplied with lubricant in any appropriate manner, as for example, by the provision of a wick or the like.

In Figure 3 there is shown a modification of the supporting bearing for the sign structure. In this form the post 20 has the upper end thereof cupped as at 21 to receive a single bearing ball 22. The upper end of the supporting post 20 is surrounded by a shell 23 105 which is designed to receive a lubricant and within the shell and snugly engaging the post 110

is a steel sleeve 24, the upper end of which is closed as at 25 and against which the ball 22 is pressed when the sign is mounted in position. The wall of the sleeve 24 is apertured as at 26 to permit grease to pass from the shell 23 to the friction ball and to lubricate the contacting surfaces between the post and the sleeve 24. The upper end 25 of the sleeve has a threaded stud 27 projecting therefrom, which stud extends through the plate 28 which is secured to the top rail of the outer frame of the sign structure, and receives a securing nut 29, by means of which the parts are held in assembled relation.

15 A particular feature of the sign embodying the present invention resides in the construction of the pockets whereby very little wind is required to rotate the sign, the air pockets 8 being so arranged that they will 20 catch the slightest breeze, thus causing the sign to move in the manner desired.

From the foregoing description, it will be seen that the herein described sign structure is of a novel character, will be inexpensive to construct and set up, and will be more efficient in bringing advertising matter to the attention of the public because of the fact that, unlike other rotating signs, it will not revolve too rapidly to permit passersby to 25 read the advertising matter thereon, and at the same time the motion will be sufficient to draw the attention of the passersby and to give them a chance to see both faces of the board.

30 Having described my invention what I claim is:—

1. In a sign structure, a sign board, a vertical supporting shaft having one end extending through the board from one edge thereof

to an opposite edge, anti-friction elements 40 surrounding the shaft within the board and adjacent said edges, and means for maintaining the shaft in vertical position.

2. In a sign structure, a sign board, a vertical supporting shaft extending at one end through the board from one edge to an opposite edge, anti-friction elements surrounding the shaft adjacent said edges, means for supporting and maintaining the shaft in vertical 45 position, means for supporting the sign board 50 at one edge upon the shaft supporting means, and anti-friction elements between the board and the supporting means therefor.

3. In a rotatable sign, a relatively broad frame, a sign board comprising a relatively 55 narrow frame having a panel overlying each side and formed to fit in the broad frame at an angle with respect to the side faces thereof, forming an air pocket at each end and at opposite faces, bearings formed intermediate 60 the ends of two opposite side members of the frames, and a supporting shaft extending through said bearings and between the panels of the board.

4. In a rotatable sign, a frame, a sign panel 65 positioned within said frame at an angle with respect to the side faces thereof to form an air pocket at each end and upon opposite faces, a bearing arranged intermediate the 70 ends of one longitudinal edge of the structure, and a supporting shaft designed to be arranged in upright position and to extend through the side structure from one longitudinal edge to the other and to engage said bearing at its upper end. 75

In testimony whereof I hereunto affix my signature.

FRED L. HINKS.
